UNITED STATES PATENT OFFICE.

ROBERT FORSYTH, OF NEW YORK, N. Y.

GRINDING-MACHINE.

1,308,008.

Specification of Letters Patent. Patented June 24, 1919.

Application filed December 23, 1916, Serial No. 138,557. Renewed September 23, 1918. Serial No. 255,383.

To all whom it may concern:

Be it known that I, ROBERT FORSYTH, a citizen of the United States, residing at New York, in the county of New York and State 5 of New York, have invented new and useful Improvements in Grinding-Machines, of which the following is a specification, reference being had to the accompanying drawings, forming a part thereof.

10 The purpose of this invention is to provide improved apparatus for grinding or pulverizing ores and the like to reduce them to a uniform degree of fineness, and substantially to a fine flour when so desired. It consists in 15 the elements and features of construction shown and described as indicated in the claims.

In the drawings:

Figure 1 is a partly sectional top plan 20 view of a machine embodying this invention, the cap or cover being removed and a portion of the frame being broken away to disclose details, section being made in the horizontal plane of the axis of one of the rotating members or disks.

Fig. 2 is a vertical section of the same in a plane transverse to the axes of the rotating members showing the latter in elevation.

Fig. 3 is a detail top plan of the central 30 portion showing the hopper opening in relation to the disks.

Fig. 4 is an outer side elevation of one of the pulverizing disks.

Fig. 5 is a detail top plan view of the receiving mouth or hopper of the machine, as 35 formed by the casing and the conical pulverizing disks therein.

The machine shown in the drawings comprises a base frame, A, which is mounted by 40 its marginal portion upon a substantial foundation or supporting structure, B, within which the pot or casing forming a hopper, C, depends, said hopper being mounted upon the base frame, A, and inclosing the crushing 45 disks, D and D¹, which are mounted for rotating about parallel axes on their respective shafts, E and E¹, which are journaled on the base frame, A. The two disks, D and D¹, are frusto-conical in form of the same taper, and 50 are mounted on their shafts oppositely positioned so that their sloping sides face each other and may come into contact as shown in Fig. 1. Each of the shafts, E and E¹, has a driving pulley, F, said driving pulleys being 55 of the same diameter, so that being driven by belts from equal pulleys on the same

counter shaft, not shown, they cause the two disks to be revolved at the same rotary speed, the two disks being revolved in opposite directions around their respective axes, one 60 of the driving belts being twisted for this purpose when they are both driven from the same counter shaft as above suggested. The two disks thus have the same direction of circumferential movement at their proximate surfaces.

The material to be pulverized is delivered into the hopper, G, whose discharge mouth at its lower end is seen as g,—a narrow parallelogrammatic rib directly overhanging 70 the line of contact or approximation of the two disks, D and D¹, for determining the pressure with which the two disks operate upon material fed between them for crushing, and to determine it in such a way that 75 the disks may separate in case any object should be delivered into the hopper too hard to be crushed between the disks by the pressure at which it is safe to operate them, such pressure is produced by means of a spring, 80 H, coiled about the shaft, E, of one of the disks, and bearing against the back or broader base of that disk when put under tension by a collar, J, screwed onto the shaft, which is threaded for that purpose, a jam 85 nut, K, being provided to prevent loosening. The fineness of the product is determined by the relative adjustment of the disks for separation of their sloping faces, and this is effected by adjusting the disk, D, by means of 90 the collar, L, screwed on the shaft abutting the narrower base of the disk, D, and retained by a jam nut, M. N represents a cushioning washer interposed between the collar L and the narrower base of the disk, 95 D, to cushion the return of the disk against the collar when it is crowded away from it by the passage of an uncrushable body between the two disks.

All the journal bearings of the shaft E 100 and E¹, are preferably roller bearings, and most preferably ball bearings, as shown in respect to one of them which is represented in axial section in Fig. 3. Each journal box, R, is chambered to afford lubricant 105 space r; and the complete ball bearings comprising the balls and the inner and outer ball races and the retaining collars, is entered through the inner open end of said chamber, r, to a shoulder r¹, provided for 110 the purpose, the end then being closed around the shaft by an annular collar, R¹,

A thrust bearing is provided for each of the shafts at the end toward which the shaft is thrust by the resistance of the material which is passed between the disks for 5 grinding. These thrust bearings are identical for the two shafts, E and E¹, that of the shaft, E, being shown in Fig. 3, comprising two plates, U and U¹, of tool steel, concaved on their proximate faces, having 10 intervening between them and seating on said concave faces a hard gun-metal double-convex lens shaped member V. The member, U, is designed to be held rigidly in a socket provided in the outer end of the journal box, and the member, U¹, may be forced onto the end of the shaft so as to be rigid therewith. In rotation of the shaft the lens member, V, may be said to float between the two parts, U and U¹, revolving somewhat with the shaft upon the member, U, the shaft however having some rotary motion upon the said lens; that is to say, the friction resulting from end thrust being divided between the two surfaces of the lens 20 as the shaft revolves; and said lens-shaped member, V, being peripherally unrestrained with respect to the adjacent concave-faced members, U, it is left free to accommodate itself with respect to both the opposed concave faces in case of any inaccuracies of 30 alinement of the axis of the shaft with the axes of the cavity of either or both of said concave faces.

The most important and essential feature of the construction is the character of the disks D and D¹. These disks are made of semi-steel, or all steel, of a tough but fairly soft character, being bored to accommodate the shaft which is properly keyed 35 thereto, the disk, D¹, being fixed in position upon the shaft E¹ and the disk, D, being mounted for sliding on the shaft E by means of a key d, the periphery and the conical face of the disk being smooth. Cores are 40

let in on the back of each disk to form 45 dovetail pockets d³ which may be filled more or less with soft metal for balancing the disks. The important feature of the operation of these disks is, that, being of soft metal, they permit the embedding of the 50 material to be ground into their faces rotating upon each other, thus forming upon each disk a grinding surface of the consistency and character of the material which is being ground; said material as it is 55 crushed having its finest particles embedded in the surface of the disk so that said surface becomes a grinding surface entirely by virtue of this embedded material, and not by virtue of the original character of the 60 surface, which as stated is machined perfectly smooth. The result of this construction and method of operation is that the disks do not wear away at all in performing their function of grinding, because the 65 entire grinding surface is furnished to them by the material ground, and therefore constantly renews itself.

I claim:—

A pulverizer or grinder comprising two 70 metal disks each frusto-conical in form journaled for rotation with their conical surfaces facing each other, and means for revolving them in opposite directions about their respective axes, whereby they have the 75 same direction of circumferential movement at their proximate surfaces, each disk being formed as to its conically surfaced portion of comparatively soft and tough metal adapted for embedding the pulverized material which is passed between the disks and crushed thereby.

In testimony whereof I have hereunto set my hand at New York this 23 day of February, 1916.

ROBERT FORSYTH.
